CLAIM

We claim the ornamental design for a luminaire, as shown and described.

DESCRIPTION

FIG. 1 is a perspective view of a luminaire according to a new design.

FIG. 2 is a front end view of the luminaire of FIG. 1.

FIG. 3 is a rear end view of the luminaire of FIG. 1.

FIG. 4 is a first side elevation view of the luminaire of FIG. 1.

FIG. 5 is a second side elevation view of the luminaire of FIG. 1.

FIG. 6 is a first plan view of the luminaire of FIG. 1.

FIG. 7 is a second plan view of the luminaire of FIG. 1; and, FIG. 8 is a front end view of the luminaire of FIG. 1, with an optic positioned over the light-emitting element.

The elements shown in broken lines are included for the purpose of illustrating portions of the luminaire that form no part of the claimed design. The dash-dot-dash lines indicate edges of a symbolic break in length. The appearance of the article between these break lines formed no part of the claimed design.
